(57) **CLAIM**

The ornamental design for a flexible package for golf ball sleeves, as shown and described.

DESCRIPTION

FIG. 1 is a perspective view of a flexible package for golf ball sleeves showing our new design;
FIG. 2 is a top plan view thereof;
FIG. 3 is a first side plan view thereof;
FIG. 4 is the other side plan view thereof;
FIG. 5 is a bottom plan view thereof;
FIG. 6 is a bottom end view thereof; and,
FIG. 7 is a top end view thereof.

The parts shown in broken lines in FIGS. 1–7 are shown for illustrative purposes only and form no part of the claimed design.
